UNITED STATES PATENT OFFICE

HUGO A. DZIEWECZYNISKI, OF CLEVELAND, OHIO

AUTOMATIC NEEDLE-FEEDING MECHANISM FOR TALKING MACHINES

Application filed December 19, 1927. Serial No. 241,069.

This invention is a stylus or needle holder and feeding mechanism for talking machines, phonographs and the like, and relates more particularly to an automatic stylus feeding mechanism adapted to be supported upon the sound box of the talking machine to which it is applied.

One object of the invention is to provide an apparatus of the type indicated wherein a reciprocable plunger functions to force needles successively from a magazine into the needle holder, there being associated with said plunger means to prevent jamming of the needles either in the magazine or in the holder.

Another object of the invention is to provide an automatic stylus feeding apparatus which will operate to eject a used needle or stylus from the stylus holder as a new needle is being inserted therein.

A further object of the invention is to provide a needle holder in which needles may be inserted and removed either manually or automatically and in which means are provided for adjusting the degree of frictional tension applied to the needles to retain them securely within the needle holder.

These and other objects of the invention will become apparent from a reading of the following specification, taken in connection with the accompanying drawings, wherein:

Fig. 1 is an elevation of the apparatus mounted in operative position upon the sound box of a reproducing machine, with the cover or casing removed.

Fig. 2 is a sectional view taken on the line 2—2 of Fig. 1.

Fig. 3 is a detail perspective view of the needle or stylus holder.

Fig. 4 is a view similar to Fig. 1, showing the plunger in its lowermost position, the cover being shown in place and broken away to disclose the parts within.

Fig. 5 is an enlarged sectional view taken on the line 5—5 of Fig. 4, showing the assembly of the needle magazine within the magazine support.

Fig. 6 is a detail perspective view of a needle magazine.

Fig. 7 is an enlarged perspective view of the plunger regulating ratchet spring.

Fig. 8 is a detail view showing the relative positions of the segmental gear and ratchet spring as the plunger is being retracted.

Fig. 9 is an enlarged perspective view of the stylus clamping block.

Referring more particularly to the accompanying drawings wherein like reference numerals designate like parts throughout, the numeral 1 indicates generally a sound box of any approved construction, having the usual elbow or nipple 2 for attachment to the tone arm of the machine, and a diaphragm 3. The diaphragm may be mounted upon the sound box in any convenient manner, said mounting means conveniently including a ring member 4, to which is secured a plate or disk 5 upon which is mounted the apparatus forming the essential features of the present invention, it being apparent that by so mounting the apparatus the same may be attached to and removed from sound boxes of general construction, without necessitating the modification thereof.

To this end the plate 5 carries a needle magazine support or slide 6, said support as shown in Fig. 5, comprising a relatively flat, rectangular tubular section 7, adapted to receive a needle magazine 8, to be referred to more particularly hereinafter. The support 6 is provided with a closed rear wall 9 and an open front wall, the edges 10—10 of which are flared outwardly to provide a pair of longitudinally extending flanges 11 upon which is slidably mounted a follower 12. The follower 12 carries complementary flanges 13—13 cooperating with the flanges 11 of the magazine support, whereby to retain the follower in operative engagement with the support. The follower also carries a block 14 which extends into the needle magazine 8 through the open front wall thereof to engage the needles therein contained and urge them toward the forward end of the magazine.

The magazine support or slide 6 is secured to the disk 5 by suitable bolts or screws 15 in a position substantially at right angles to the vertical diameter of the disk, as clearly shown in Figs. 1 and 4, whereby needles from

the magazine 8 may be projected into the vertical needle holder 16, which will be more fully referred to hereinafter. The magazine 8 as shown more clearly in Fig. 6, comprises a tubular sheet metal container substantially rectangular in form and having a closed rear wall 17 and an open front wall, the latter being defined by inturned longitudinal flanges 18. The forward end of the magazine is provided with an arcuate stop 19 designed to form an abutment against which the needles contained in the magazine are urged by the follower 12, hereinbefore referred to and which operation will be more fully described hereinafter. The magazine 8 is provided at its opposite extremity with a down-turned tang 20 for facilitating the insertion and removal of the magazine 8 with respect to the magazine support or slide 6. Furthermore, it may be found desirable to provide suitable locking tongues 21, as shown in dotted lines in Fig. 6, for the purpose of preventing the accidental loss of needles from the open rear end of the magazine, it being apparent that after the magazine has been filled with needles the said tongues 21 may be bent down over the open rear end of the magazine. This expedient is quite desirable when it is desired to supply filled magazines to the trade as an article of commerce.

It is to be noted that the magazine 8 is of a length such that when positioned in the magazine support 6 with the tang 20 abutting against the free end of the support the first needle in the magazine, namely, the one within the arcuate stop or abutment 19, is directly above the needle channel 16^a in the needle holder 16. Also, the stop or abutment 19 is open at the top and bottom as shown at 22 in Fig. 6, for permitting the entrance of the needle ejecting plunger to transfer a needle from the magazine into the holder.

The rear wall 9 of the magazine support 6 is preferably cut away slightly between the flanges 11, at the free extremity thereof, in order to provide for the reception of the tang 20 of the magazine 8, it being apparent that by so designing these elements, provision is made for the longitudinal extent of the flanges 13 of the follower block 12 between the end of the magazine and the free end of the magazine support when a freshly filled magazine has been inserted into the support.

As shown in Fig. 5 the needles are arranged in the magazine 8 transversely thereof and parallel to one another with the points down, and in order to successively feed the needles into proper position above the needle holder 16, the follower 12 is resiliently tensioned against the strip of needles by means of a flexible cord 23, preferably non-metallic, such as catgut or the like, and a spring roller or reel 24, the cord 23 being secured to the follower 12 in any convenient manner, and thence trained about a guide pulley 25, from

which it is carried and secured to the spring roller 24, the latter being arranged upon a suitable spindle 26 secured to the disk 5, and designed, by reason of a coil spring 27, to maintain the cord 23 under a suitable degree of tension whereby the needles in the magazine 8 are constantly urged into engagement with the abutment 19.

The needle ejecting mechanism is arranged upon the disk 5 above the magazine support 6 and comprises a vertically reciprocable plunger 28 and an operating lever therefor, 29. The plunger 28 carries at its upper end a suitable rack 30 and is confined for vertical reciprocation by upper and lower guide members 31 and 32. The upper guide member 31 is shown as a U-shaped sleeve member having its open face erected toward the operating lever 29, whereby the rack 30 carried by the plunger may operatively engage a segmental gear 33 carried by the adjacent extremity of the lever 29. The lower guide member 32 may be of any suitable design, such as will embrace the lower end of the plunger and retain the same in substantially vertical alignment with the opening 22 of the needle magazine and the needle groove 16^a in the needle holder 16, and is shown in the drawings as a perforated lug carried by the disk 5. It is apparent that either or both of the guide members 31 and 32 may be formed of suitable sheet metal as separate elements and then secured to the disk 5, or they may be stamped from the disk itself, if desired, and this materially reduces the cost of manufacture without sacrificing the efficiency of operation.

The operating lever 29 above referred to, is pivotally secured to the disk 5 by a suitable stud 34, and a coil spring 35 is arranged about said stud with its opposite ends secured to the disk and lever at points 35^a and 35^b, respectively, said spring functioning to urge the lever for pivotal movement about the stud in a counter-clockwise direction so that the plunger may be maintained in an elevated position, as shown in Fig. 1. It is, therefore, apparent that upon rotation of the lever 29 in a clockwise direction about the stud 34, the plunger 28, due to the engagement between the gear 33 and the rack 31, is moved vertically downward to the position shown in Fig. 4, and that when the lever 29 is released the coil spring 35 will function to retract the plunger as above described. If desired a suitable lug or grip A may be conveniently provided on the ring member 4, in order to facilitate the operation of the lever 29.

In order to regulate the movement of the plunger and insure a full down stroke before the coil spring 35 will be effective to retract the plunger, a ratchet mechanism is provided which functions to lock the operating lever 29 against counter-clockwise rotation if said lever is released before the plunger

er has completed its full down stroke. The ratchet mechanism comprises an arcuate segmental rack 36 carried by the lever 29 and a cooperating spring detent 37 mounted upon the disk 5 and arranged to bear against the rack 36. The spring detent as shown in Fig. 7 comprises a plate 38 provided with suitable apertures or screw holes 39 by which the same is secured to the disk 5, and as carrying an upstanding spring arm 40. The spring arm 40 carries at its outer free extremity a laterally extending tooth or wing 41 arranged to engage the teeth of the rack 36. As shown in Fig. 1 the detent 37 is secured to the disk 5 in a manner such that the tooth or wing 41 of the arm 40 resiliently engages the rack 36, the teeth of which are so arranged as to form a locking engagement between the lever 29 and the detent 37 to prevent counter-clockwise rotation of the lever 29 when moved from the position shown in Fig. 1 to a position of less angular displacement than that shown in Fig. 4.

To ensure the release of the ratchet mechanism upon a rotation of the lever 29 sufficient to cause a complete downward movement of the plunger, the lever 29 carries a ratchet tooth guard comprising an arcuate leaf spring 42 positioned adjacent to the rack 36 and between it and the free end of the lever. This spring 42 is arranged to resiliently bear against a cam portion 43 located at the far extremity of the rack 36 so that, as the wing 41 rides off of the last tooth of the rack and on to the cam 43, the wing 41 will pass on said cam beneath the end of the spring 42 and thence, when the lever 29 is released, will ride up onto said spring 42, as shown in Fig. 8. It is thus apparent that the wing 41 is held clear of the ratchet 36 during the counter-clockwise rotation of the lever 29 until said lever has resumed a normal position, as shown in Fig. 1, at which time the wings 41 will have cleared the lower end of the spring 42 and will, therefore, drop back in operative position upon the rack 36. The spring 42 may be secured to the lever 29 in any convenient manner, such as by providing it with a laterally extending attaching flange 44.

The needles as they are ejected from the magazine 8 are forced into a stylus holder 16, pivotally mounted upon the sound box, beneath the magazine support 6. The stylus holder as shown in Fig. 4 comprises a block 45 pivotally mounted in the usual manner between ears 46 carried by the sound box. The block 45 carries the usual diaphragm actuating lever 47, said lever being carried over the disc 5 and through a conveniently arranged aperture 48 therein into operative engagement with the diaphragm.

It will be noted that the diaphragm operating lever 47 is disposed to one side of the central vertical axis of the block 45. This

disposition of the lever 47 makes possible the central location of the needle slot or channel 16a in the block 45. The needle slot 16a extends vertically from the block 45 and opens, throughout its length, through the front face of the block 45. A stylus clamping block 50 is positioned in the needle slot 16a, said block extending from the forward face of the stylus holder into inoperative relation with the tensioning spring 52.

As shown more clearly in Figs. 3 and 9, the stylus clamping block 50 is provided on its rear face with a longitudinal, rounded groove 50a adapted to cooperate with the rounded wall of the needle slot 16a to form a substantially cylindrical needle chamber. The front face of the block 50 is provided with a dove tailed notch 53 designed to receive the tensioning spring 52 which, as shown in Fig. 3, is secured by screws 51 adjacent its ends to the front face of the stylus holding block 45. The block 50 is dimensioned so that the bottom wall 54 of the dove tailed notch 53 normally lies above the plane of the front face of the block 45 so that by adjustment of the screws 51 the spring 52 may be placed under any desired degree of tension whereby to hold the needles within the slot 16a with any desired degree of firmness. If desired one or both ends of the spring 51 may be slotted adjacent the screw holes therein to provide for the relative movement between these parts during adjustment. Furthermore, the block 45 may be provided with a second needle receiving channel and retaining set screw 55 of the usual type for this purpose of providing a manually operable needle holder to be used in lieu of the automatic needle fitting mechanism herein described.

In operation, assuming a filled magazine 8 has been inserted in the magazine support 6 so as to bring the first needle into alinement with the plunger 28 and the needle groove of the block 45, the lever 29 is operated to rotate the same in a clockwise direction. This movement, due to the engagement between the gear 33 and the rack 30, functions to depress the plunger 28. The plunger in its downward movement engages the top end of the first needle within the magazine 8 and ejects it through the bottom opening 22 of the magazine into the needle groove 16a immediately therebeneath. The plunger 28 is of a diameter slightly less than that of the needle upon which it operates so that the needle is firmly gripped between the blocks 45 and 50, while the plunger, under the action of the spring 35 is retracted to the position shown in Fig. 1, the retraction of the plunger 28 from the arcuate abutment 19 of the magazine 8 allowing the next succeeding needle to move against said abutment under the action of the spring drawn follower 12. Upon subsequent operation of the lever 29

the plunger 28 acts upon the needle in the stop 19 in the same manner as above described, it being noted that in this instance the needle already in the block 45 is ejected by the entrance of the new needle being inserted. It is to be here noted that as above suggested, that if the lever 29 is released before being moved a distance sufficient to cause a complete down stroke of the plunger, the ratchet spring 37 will lock in the rack 36 to prevent counter-clockwise or retrograde movement of the lever and plunger. This ensures positive operation of the apparatus and prevents jamming of the needles, due to a partial depression of the plunger.

Preferably the entire apparatus hereinbefore referred to and mounted within the confines of the disk 5, is enclosed in a suitable cover or casing, the latter being provided with an appropriate side slot through which the operating lever 29 may extend.

From the foregoing description it is apparent that the present invention provides an automatic stylus feeding mechanism for talking machines, that is simple and positive in its operation, easy and economical of manufacture and one wherein means are provided to ensure against jamming of the needles in the magazine or holder.

In conclusion it is to be noted that while I have here shown and described a preferred embodiment of my invention, such description and illustration are for the purpose of example only and are not to be construed as defining the limits of my invention, which are to be determined from the scope of the appended claims.

Having thus described my invention, which I claim as new, is:—

1. The combination with a sound box of a talking machine, including a stylus holder, of a reciprocable plunger mounted above the stylus holder and in alinement therewith, a stylus magazine positioned between the stylus holder and plunger, and means to reciprocate the plunger to transfer a stylus from the magazine to the holder, said means including a pivoted lever, a rack carried by the plunger, and a segmental gear carried by the pivoted lever and meshing with the plunger rack.

2. The combination with the sound box of a talking machine, including a stylus holder, of a reciprocable plunger mounted above the stylus holder and in alinement therewith, a stylus magazine positioned between the plunger and stylus holder, a pivoted lever associated with the plunger, a segmental gear carried by the lever, a rack carried by the plunger, said rack and gear intermeshing whereby pivotal movement of the lever causes reciprocation of the plunger to transfer a stylus from the magazine to the holder, means associated with the lever to restore the plunger to a predetermined normal position

when the lever is released, and means to render said last mentioned means ineffective until said plunger is moved to a predetermined position.

3. A needle feeding mechanism for talking machines comprising a base, a needle magazine mounted thereon, a reciprocable plunger operatively associated with the magazine, a rack carried by the plunger, and a pivoted operating lever for the plunger, said lever being provided with a segmental gear arranged to mesh with the teeth of the plunger rack, whereby operation of the pivoted lever causes reciprocation of the plunger to eject needles from the magazine.

4. A needle feeding mechanism for talking machines, comprising a base, a needle magazine mounted thereon, said magazine being provided with an abutment at its forward end open at top and bottom, a reciprocable plunger mounted above the magazine and in alinement with the openings in said abutment, means to reciprocate the plunger to eject needles from the magazine through the opening in the bottom of the abutment, said means including a rack carried by the plunger, and a pivoted lever mounted adjacent the plunger, said lever carrying a segmental gear intermeshing with the plunger rack whereby pivotal movement of the lever causes reciprocation of the plunger.

5. A needle feeding mechanism for talking machines, comprising a base, a needle magazine mounted thereon, said magazine being provided with an abutment at its forward end open at top and bottom, a reciprocable plunger mounted above the magazine and in alinement with the openings in said abutment, means to reciprocate the plunger to eject needles from the magazine through the opening in the bottom of the abutment, and means to successively move the needles in the magazine against said abutment and into alinement with the plunger, including a follower block slidingly mounted with respect to the magazine and in engagement with the needles therein, a flexible strand attached to said block at one end and to a roller at the other end, and resilient means associated with the roller tending to wind the strand thereon whereby the follower block is held in resilient engagement with the needles.

6. A needle feeding mechanism for talking machines including a needle magazine having an open front wall, means for ejecting the needles from the magazine, a magazine support having an opening in one wall, the opening in the magazine wall registering with the opening in the wall of the magazine support, and a spring drawn follower slidingly mounted upon the magazine support and engaging the needles in the magazine through said registering openings whereby

the needles are successively moved into operative position with respect to the ejecting means.

7. A needle feeding mechanism for talking machines including a needle magazine having an elongated opening in one wall thereof, and a needle stop at its forward end, a magazine support having an elongated opening in one wall registering with the opening in the wall of the magazine, a follower, slidingly mounted upon the magazine support and arranged to engage the needles in the magazine through said registering openings, a reciprocable plunger arranged above the magazine in alinement with the needle stop and operable to eject the needles from the magazine, and resilient means associated with the follower to move the needles successively into engagement with the needle stop.
- 20 8. A needle feeding mechanism for talking machines described in claim 7 wherein the resilient means associated with the follower block comprises a spring roller and a flexible strand having one end secured to the roller and its other end secured to the follower block.

9. A needle feeding mechanism for talking machines, comprising a needle magazine, a reciprocable plunger operable to eject the needles from the magazine, manual means to move the plunger to ejecting position, automatic means to retract the plunger from such position, and means to render said automatic means ineffective until the plunger has moved to a predetermined position.

- 40 10. A needle feeding mechanism for talking machines including a reciprocable plunger operable to successively eject needles from a needle magazine, manual means to move the plunger to ejecting position, means tending to automatically retract the plunger when said manual means is released, and means rendering said automatic means ineffective until the plunger has been moved to a predetermined position.

- 50 11. A needle feeding mechanism for talking machines described in claim 10, wherein the manual means for moving the plunger comprises a pivoted lever carrying a segmental gear at one end, and a rack carried by the plunger, said rack and gear intermeshing, and wherein the automatic plunger retracting means comprising a spring associated with the pivoted lever and tensioned to move the lever to elevate the plunger.

- 60 12. A needle feeding mechanism for talking machines including a reciprocable plunger operable to successively eject needles from a needle magazine, a rack carried by the plunger, a pivoted lever to operate said plunger, said lever carrying a segmental gear intermeshing with the plunger rack, a spring associated with the lever tending to automatically retract the plunger when the lever is

released, and a ratchet mechanism associated with the lever for locking the lever against retrograde movement if released, before the plunger is moved to a predetermined position.

- 70 13. A needle feeding mechanism for talking machines including a reciprocable plunger operable to successively eject needles from a needle magazine, a rack carried by the plunger, a pivoted lever for operating the plunger, said lever carrying a segmental gear intermeshing with the plunger rack, a spring associated with the lever tending to automatically retract the plunger whenever the lever is released, a ratchet mechanism for locking the lever against retrograde movement if released before the plunger is moved to a predetermined position, and means to render the ratchet mechanism ineffective when the lever is moved to said predetermined position.

- 75 14. A needle feeding mechanism for talking machines including a reciprocable plunger operable to successively eject needles from a needle magazine, a rack carried by the plunger, a pivoted lever for operating the plunger, said lever carrying a segmental gear intermeshing with the plunger rack, a spring associated with the lever tending to automatically retract the plunger whenever the lever is released, a ratchet mechanism for locking the lever against retrograde movement if released before the plunger is moved to a predetermined position, and means to render the ratchet mechanism ineffective when the lever is moved to said predetermined position.

- 80 15. A needle feeding mechanism for talking machines including a reciprocable plunger operable to successively eject needles from a needle magazine, a rack carried by the plunger, a pivoted lever for operating the plunger, said lever carrying a segmental gear intermeshing with the plunger rack, a spring associated with the lever tending to automatically retract the plunger whenever the lever is released, a rack carried by the lever, a detent operatively associated with the rack and functioning to lock the lever against retrograde movement whenever said lever is released, a cam positioned on the lever adjacent to the rack, and a leaf spring overlying said rack and engaging said cam whereby when the plunger is moved to said predetermined position the detent will pass from the rack onto the cam under the end of the leaf spring,

needles, a track member associated with the magazine support and a follower slidable upon the track, said follower extending through the registering openings into engagement with the needles in the magazine, and means to successively eject needles from the magazine.

17. A needle feeding mechanism for talking machines comprising a magazine support, a needle magazine removably mounted within the magazine support, respectively adjacent walls of the support and magazine being provided with registering openings, the opening in the wall of the magazine support being defined by longitudinally extending flanges, a spring follower slidably mounted upon the flanges and extending into the magazine through the registering openings, and means to successively eject needles from the magazine.

18. In a needle feeding mechanism including a needle magazine, a reciprocatory plunger for ejecting needles therefrom and means including a pivoted lever for actuating the plunger; the combination with the plunger actuating means, of means to insure a complete stroke of the plunger comprising a rack associated with the lever, a spring pressed pawl engaging the rack and locking the lever against retrograde movement in intermediate positions of the plunger, a guard member associated with the rack and means to move the pawl clear of the rack and onto the guard when the lever has moved the plunger to the full extent of its stroke whereby to release the lever for retrograde movement.

19. In a needle feeding mechanism including a needle magazine, a reciprocatory plunger for ejecting needles therefrom and means including a pivoted lever for actuating the plunger; the combination with the plunger actuating means, of means to insure a complete stroke of the plunger comprising a rack associated with the lever, a spring pressed pawl engaging the rack and locking the lever against retrograde movement in intermediate positions of the plunger, a guard member overlying the rack, a cam member at the end of the rack and engageable with the pawl to move the same from the rack to the guard when the lever is moved to its extreme position whereby to release the lever for retrograde movement.

55. In testimony whereof I hereunto affix my signature:

HUGO A. DZIEWECZYNISKI.
